Specification of Letters Patent.

Patented Apr. 5, 1910.

Application filed January 28, 1909. Serial No. 474,749.

To all whom it may concern:

Be it known that we, RICHARD L. SUSEMIEL, a citizen of the United States, and THEODOR SUSEMIEL, a subject of the German Emperor, and both residents of the city of New York, borough of Brooklyn, in the county of Kings and State of New York, have invented a new and Improved Umbrella, of which the following is a full, clear, and exact description.

This invention relates to umbrellas, and more particularly to a folding umbrella comprising a rod formed in sections which can be disjointed, and a folding frame carried by one of the sections, the folding frame comprising a runner, sectional ribs pivotally secured together, and stays secured to the runner, the stays being pivoted at the inner ends of the outer rib sections, the rib sections being arranged to fold back upon each other, and the runner being so arranged that it can be positioned adjacent to the notch, whereby the stays and the rib sections can be arranged in juxtaposition to form a compact bundle substantially equal in length to half the length of a rib.

An object of the invention is to provide a simple, inexpensive and durable folding umbrella, which can be disjointed and folded into a compact form, which takes up but very little space, which is easily manipulated both in opening and closing the umbrella and in folding it, and which is strongly constructed, so that sudden gusts of wind or the like cannot easily injure or disarrange the frame.

A further object of the invention is to provide a folding umbrella in which the cover is permanently associated with the folding frame, in which the ribs are formed of jointed sections so that they can be folded upon themselves to occupy a space equal in length to approximately half the length of a rib, in which the section which carries the folding frame is separable from the other sections of the rod, the other sections being flexibly jointed so that they can be folded upon each other, and in which different forms of ribs and other parts can be employed.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is an elevation showing the rod, one of the ribs, and a stay of an umbrella constituting an embodiment of our invention and having the cover removed therefrom; Fig. 2 is a similar view showing certain of the parts being folded; Fig. 3 is a similar view showing the rods and the stays being arranged in their final folded position; Fig. 4 is an enlarged elevation showing a part of the rod and the runner slideable upon the same; Fig. 5 is a longitudinal section showing a part of the rod and the runner; Fig. 6 is an enlarged elevation showing the connection between the separable sections of the rod; Fig. 7 is an enlarged longitudinal section showing the adjacent ends of the separable sections and the means for connecting them; Fig. 8 is an enlarged side elevation showing the pivoted connection between the rib sections or members and the stays; Fig. 9 is a plan view of the parts illustrated in Fig. 8; Fig. 10 is an enlarged side elevation showing the inner end of an outer rib member of modified form; Fig. 11 is an enlarged elevation of a part of the rod showing the adjacent ends of the flexibly connected sections and having a part in longitudinal section; Fig. 12 is a longitudinal section of the parts illustrated in Fig. 11; and Fig. 13 is an enlarged elevation showing the adjacent ends of the flexibly connected rod sections in a folded position.

Before proceeding to a more detailed explanation of our invention it should be clearly understood that while the same is particularly useful in connection with umbrellas, it can also be advantageously applied to other similar devices such for example, as parasols or sun-shades.

In the accompanying drawings we have illustrated a type of our invention in which the ribs are of circular cross section, while the stays are of the conventional "paragon" kind and are of U-section, it will be seen that we can employ either form or rib or stay as desired. This detail of construction as well as others of those set forth herewith, can be varied in accordance with individual preference and special conditions, without

departing from the underlying spirit of our invention, and we do not wish to limit ourselves to such constructive details.

Referring more particularly to the drawings, we provide an umbrella rod 10 consisting of a plurality of sections preferably three in number. In the form of the device shown for example, in the accompanying drawings, the rod consists of the sections 11, 12 and 13. The section 11 at the free end, has a handle 14 of any suitable form, and the section 13 which carries the folding frame 16, has at the extremity a ferrule 15. We prefer to fashion the umbrella rod from hollow tubing as this permits of a construction that is both light and strong. The section 11 has a constricted extension or part 17 which is likewise hollow and may be secured within the end of the section by means 20 of a rivet 18 or in any other convenient manner. The part 17 has a bifurcated end in which is pivotally mounted an ear 19 by means of a pivot pin or rivet 20. The free end of the ear has secured thereto a link 21 preferably fashioned by bending upon itself a strip or band of metal so that the link has a slot 22 extending longitudinally thereof. The link is rotatably arranged within the rod section 12 and has the sides pivoted to 30 the ear 19 by means of a pivot pin or rivet 23. A cross shaft 24 extends through the section 12 and is located in the slot 22 so that it constitutes a stop to limit the movement of the link longitudinally of the section 12 and to prevent the link from being withdrawn from the section. The ear 19 permits the sections 11 and 12 to be folded together as is shown most clearly in Fig. 13, the ear forming a double-jointed connection 40 between the sections to aline and hold the sections together. The part 17 is inserted within the section 12 until the ends of the section are in juxtaposition, the link sliding within the section 12 when the latter is 45 forced home upon the part 17.

The part 17 has a slot 25 through which projects the curved end 27 of a keeper 26 located within the part 17 and having the end 28 riveted in a suitable opening of the part. The keeper is resilient and has an offset 29 engaging at the inside of the wall of the part 17, whereby the keeper tends to maintain a normal projected position at the slot 25. The rod section 12 has a slot 30 55 through which the end 27 of the keeper projects when the sections 11 and 12 are assembled to lock the parts in position. It will be understood that the keeper can be forced manually into the part 17 and out of 60 engagement with the slot 30, so that the rod sections can be disengaged.

At the end remote from the section 11, the rod section 12 has a constricted extension or part 31 secured thereto by means of a rivet 32 or the like. The part 31 is formed so

that it will fit into the open end of the rod section 13 and it has a keeper 33 similar to the keeper 26 and having the end 34 normally projecting through a slot 35 of the part 31. The keeper, further, has the end 36 riveted in a suitable opening of the part 31 and has an extension 37 engaging at the inside of the part to hold the end 34 normally projected through the slot 35. The rod section 13 has a slot 38 through which the end 34 of the keeper can project to lock the rod sections together when they are assembled.

We employ a runner 39 movable slidably upon the rod and having at the lower end 80 a flange 40 folded back upon itself and having the edge 41 at the opposite end outwardly disposed. Adjacent to the edge 41 the runner is formed into a bead 42. A notch 43 is rigidly secured upon the runner 85 near the upper end thereof and has recesses 44 to receive the ends of the frame stays 45 in the usual manner, the stays having eyes through which a tying wire 46 passes to secure the stays pivotally in place. A cushion ring 47 of rubber or other suitable resilient material is mounted upon the upper end of the runner, between the edge 41 and the notch, the cushion ring engaging the bead 42 which serves to assist in holding it 90 in place. The section 13 has located therein a spring keeper 48 having the end 49 riveted in a suitable opening of the section and having an extension 50 engaging at the inside of the section 13 to hold the end 51 of 100 the keeper normally projected through a slot 52 of the section. The end 51 of the keeper has a recess 53 adapted to engage a cross bar or stop 54 formed in a cut away part 55 of the runner. When the keeper 48 105 engages the stop 54 the runner is held in a position such that the umbrella is open or spread as will appear more clearly hereinafter. A flexible guard strip 56 is arranged longitudinally of the keeper and has one end 110 secured between the runner and the flange 40 and has the other end positioned in a suitable recess 57 of the notch of the runner. The flexible guard extends longitudinally of the cut away part 55 and permits the keeper 115 to be displaced from engagement with the stop 54 without injury to the hand of the operator.

Near the ferrule end, the section 15 of the rod has the fixed notch 58. In the recesses 120 59 of this notch are pivotally mounted the ends of the inner rib members 60. These have the outer extremities 61 turned back and arranged substantially parallel to the rib. The rib and the end 61 are downwardly curved to form seats 62 at the bends which receive and support the outer rib members 63. These terminate in the usual ball tips 64 and have eyes 65 to which the material of the cover can be sewed or otherwise se- 130

cured. The outer rib members 63 have the inner ends bent to form hooks constituting bearings 66 at which are pivotally secured joints 67 preferably fashioned by bending 5 suitably formed pieces upon themselves. The joints are secured at the parts 66 by rivet pins 68 or the like. The stay rods 45 at the outer ends have brackets 69 movably secured to the joints 67 by means of rivet pins 70 10 or the like.

Each inner rib member 60 and its rearwardly disposed end 61 at corresponding opposite points have rigidly secured thereto sleeves 71 and 72 brazed or otherwise fastened thereon. These sleeves have downwardly disposed ears 73. Each outer rib member 63 has a similar sleeve 74 secured thereto which likewise has downwardly disposed ears and is located between the sleeves 15 71 and 72. A rivet pin 75 is passed through the ears to attach the outer rib member pivotally to the inner rib member. Each of the outer rib members has rigidly secured thereto a sleeve 76 having a downwardly disposed 20 part 77 which carries a button or projection 78 adapted to engage at the end 61 of the corresponding inner rib member when the umbrella is spread, as is shown most clearly in Figs. 8 and 9. This projection 78 constitutes a locking stop to hold the rib members 25 extended. It can be forced past the end 61 of the inner rib member to assume a position under the same, as the rib members have a normal resiliency due to the material of which they are constructed. To fold the outer rib back upon the inner rib member it is necessary to force the locking stop upwardly beyond the end 61. This can be accomplished without difficulty by manual 30 pressure, but the stop affords sufficient resistance so that gusts of wind or other accidental occurrences are not apt to disengage the frame when the umbrella is open.

Each bracket 69 is fashioned from sheet or 45 plate metal folded upon itself so that the sides 80 of the bracket can be pivoted at the outer sides of the joints 67. The end 69 of the stay 45 is flattened and extends between the sides of the bracket and the side of the 50 joint 67 and is riveted between the sides of the joint by the rivet pins 70. This construction materially strengthens the connection between the stay and the rib.

The rod section 11 has a spring keeper 55 55 of the usual kind and which is adapted to engage the runner to hold the same in its lowermost position, that is, a position such that the umbrella is closed.

When the umbrella is in use the rod sections 60 60 are assembled and the rib members are extended or alined, so that the locking stops engage underneath the end 61 of the inner rib members. When the umbrella is opened the runner is arranged so that the keeper 48 65 engages the stop 54. The ribs are then

spread and are held in position by the stays 45. When it is desired to close the umbrella the runner is released from the keeper 48 and is moved to engagement with the keeper 81. When it is desired to fold the umbrella 70 it is held partly closed and the outer rib members are then folded back against the inner rib members. The runner is now moved into engagement with the fixed notch, the flexible guard being held pressed 75 against the runner so that the latter can move over the keeper 48 without being held by the latter. When the runner is positioned against the fixed notch the inner rib members can swing outwardly against the rod 80 section 13 and as the outer rib members have been held back against the inner rib members, the ribs are held against the rib section 13 and in compact form. The rod sections are now taken apart and with the folded 85 frame can be placed in a suitable receptacle or cover. The cushion rings 47 permit the runner to be brought sharply against the fixed notch without injury to either of these parts. 90

The cover may be of any suitable form or such as is usually employed in umbrellas or like devices and may be attached to the frame in any convenient manner. In Fig. 10 is shown a modified form of the outer rib 95 member. This member is of cross U-section and has at the inner end a bracket 82 having an ear 83 at the extremity, which is pivoted to the joint 67. The bracket has a further ear 84 which is pivoted between the ears of 100 the sleeves 71 and 72.

Having thus described our invention, we claim as new and desire to secure by Letters Patent:—

1. In an umbrella, a rod formed in sections, one of said sections being hollow, the other of said sections having a part adapted to be inserted in said hollow section, a slotted link movable within said hollow section, a pin extending through the slot of the link 110 and limiting movement thereof, a doubly jointed connection between said link and said part, and a keeper for holding said sections together when said part is inserted within said hollow section. 115

2. In an umbrella, a rod formed in sections, one of said sections being hollow, the other of said sections having a part adapted to be inserted in said hollow section, a slotted link, an ear pivotally connected with 120 said part and said link, a stop engaging the slot of said link whereby said link has a limited movement within said hollow section, and a normally projected spring keeper carried by said part, said hollow section having a slot adapted to receive said keeper when the same is projected, whereby said sections are held together when said part is inserted within said hollow section. 125

3. In an umbrella, a rod formed in sec- 130

- tions, one of said sections being hollow, the other of said sections having a part adapted to be inserted in said hollow section, a strip bent upon itself to form a slotted link, an ear pivotally secured between the ends of said strip and pivotally connected with said part, a pin extending transversely of said hollow section at the inside thereof and between the sides of said link, whereby said link has a limited movement within said hollow section, and a keeper carried by said part and serving to hold said sections together when said part is inserted within said hollow section.
- 15 4. In an umbrella, ribs each consisting of an inner member having its end rearwardly disposed and an outer member pivoted to the inner member a short distance from its end and adapted when extended to rest 20 against the bend formed by the rearwardly disposed end, and a brace pivotally connected with the inner end of the outer member.
5. In an umbrella, a frame comprising 25 ribs each consisting of an inner rib member having the outer end rearwardly bent and offset, and an outer rib member pivotally mounted between the extremity of said rearwardly disposed end and said inner rib member, whereby said outer rib member is movably arranged between said inner rib member and said rearwardly disposed end thereof, stays each pivotally connected with the inner end of one of said outer rib members, 30 said outer rib members when extended seating at the junctions of said inner rib members and their rearwardly disposed ends, and locking attachments carried by said outer rib members and adapted frictionally to engage 35 said ends of said inner rib members to hold said members extended.
6. In an umbrella, a frame comprising 40 ribs consisting of inner rib members having the ends rearwardly disposed and offset, whereby bends are formed, said bends being downwardly disposed, and outer rib members each arranged between one of said inner rib members and its rearwardly disposed end, means for pivotally mounting 45 each of said outer rib members between one of said inner rib members and the extremity 50 of its rearwardly disposed end, the inner extremity of each of said outer rib members extending inwardly beyond the extremity of said rearwardly disposed end of the corresponding inner rib member, a runner, stays pivoted upon said runner, and a joint connecting each of said stays with the inner end of one of said outer rib members, said outer rib members having studs adapted to engage under said ends of said inner rib members to hold said members extended. 55
7. In an umbrella, sectional and hinged ribs, the outer section being hinged a short distance from its end, stays, brackets at the 60 ends of said stays and having spaced sides, said stays having the ends constricted and extending between said spaced sides of said brackets, and joints having spaced sides arranged between said ends of said stays and 65 said sides of said brackets and pivoted thereto, said joints being pivotally connected with the outer rib member. 70
8. In an umbrella, a frame comprising 75 ribs each consisting of an inner rib member and an outer rib member pivoted thereto, said outer rib members having studs, said inner rib members having offset parts adapted to be engaged by said studs to hold said rib members extended, said parts being normally resilient to permit said studs to be forced past the said offset parts. 80
9. In an umbrella, a rod, a fixed notch thereon, folding ribs pivoted at said fixed notch, a runner provided with a notch and 85 slidably longitudinally of said rod, stays pivoted to the notch of the runner and pivotally connected with said ribs, said runner at the end adjacent to said fixed notch having a bead and an outwardly disposed edge, 90 and an annular cushion member mounted upon said runner at said bead and said outwardly disposed edge. 95
